SAFETY RAZOR BLADE STROPPING HOLDER

Filed Nov. 3, 1931

UNITED STATES PATENT OFFICE

1,993,731

SAFETY RAZOR BLADE STROPPING
HOLDER

Solomon A. Behrman, Los Angeles, Calif.

Application November 3, 1931, Serial No. 572,831

2 Claims. (Cl. 30—25)

My invention relates to a holder that is especially designed for receiving and holding safety razor blades during stropping operations and the principal objects of my invention are, to 5 generally improve upon and simplify the construction of the existing forms of safety razor blade holders, to provide a holder having simple and efficient means that will firmly grip the inserted blade and hold the same in convenient 10 position while the exposed edge thereof is being stropped, further, to construct the holder so as to enable the blade to be easily and quickly inserted or removed and further, to provide a razor blade holder of the character referred to that 15 may be manipulated without undue danger of cutting the hand or fingers of the operator while the blade is being inserted in the holder or removed therefrom.

Further objects of my invention are, to provide 20 a razor blade holder of the character referred to that will receive and conveniently hold during stropping operations, practically all forms of safety razor blades that are now on the market and to construct the holder and 25 mount the blade engaging plates thereupon so that when a blade is gripped between the plates and the latter are positioned within the slotted portion of the holder the parts will be effectively held against all vibration or relative movement 30 during stropping operations and the arrangement and construction being such as to effectively prevent the blade gripping plates from tending to move out of the holder as a result of the friction developed between the blade and 35 its holder and the strop during the blade stropping operations.

With the foregoing and other objects in view, my invention consists in certain novel features of construction and arrangement of parts that 40 will hereinafter be more fully described and claimed and illustrated in the accompanying drawing, in which:

Fig. 1 is a side elevational view of a safety 45 razor blade holder of my improved construction.

Fig. 2 is a front end elevational view of the holder.

Fig. 3 is an elevational view of the holder with the blade engaging plates swung apart so as to receive or permit the removal of a blade.

Fig. 4 is an enlarged cross section taken on the line 4—4 of Fig. 1.

Fig. 5 is an enlarged cross section taken on the line 5—5 of Fig. 1.

Fig. 6 is an enlarged cross section taken on the line 6—6 of Fig. 1.

Figs. 7 and 8 are elevational views of the forward portion of the holders and showing different forms of the blade gripping plates.

Referring by numerals to the accompanying drawing which illustrates a practical embodiment of my invention, 10 designates the handle of the holder, which is preferably formed of sheet metal bent into tubular form and in order that said handle may be more firmly gripped during stropping operations, said handle is covered with a tubular member 11 of rubber or the like.

Formed integral with and projecting forwardly from handle 10, is an inverted U-shaped member 12 and a portion of this member immediately adjacent to the tubular handle 10 is cut away on the underside as designated by 13, thereby forming a short neck portion 14 that connects the handle 10 with the forward portion of the member 12. The lower portions of the walls of the material forming the neck portion 14 are curved inwardly to form inwardly projecting edges that are adapted to frictionally engage the rear portions of the razor blade holding plates that are pivoted to the forward end of the member 12 when said plates are swung into position between the walls of said member 12 to hold the blade in position for sharpening (see Fig. 6).

The lower portions of the side walls of member 12 are disposed parallel with each other to form friction plates 15 and at the forward end of member 12, these parallel lower edges are extended forwardly to form a pair of ears 16, that are perforated for the reception of a rivet 17.

Formed on this rivet adjacent to one end, is a shoulder 18, which bears against the inner face of one of the ears 16, and this construction holds the ears in proper spaced relation.

If desired the rivet 17 may be provided with shoulders such as 18 adjacent both ends, thereby properly spacing the ears 16.

Pivotedly mounted on the rivet 17, between the ears 16, are ears 19 that project forwardly from the intermediate portions of the front ends of blade receiving and clamping plates 20. These plates are formed from thin sheets of metal and the length thereof corresponds with the length of the inverted U-shaped member 12.

Formed integral with and projecting rearwardly from the upper portions of the blade clamping plates 20, are ears 21 which, when the plates are properly folded into the holder, occupy the notches or cut away portions 13 in the body of the holder and these ears 21 are pro-

vided with short longitudinally disposed slots or openings 22 that provide convenient finger holds when the plates are swung out of the holder.

5 When the plates are folded into the body of the holder, the openings 22 coincide with each other and with the notches or cut-away portions 13 and said openings enable the thumb and index finger to readily engage the rear ends of the 10 blade holding plates when the same are to be swung outwardly from their position between the walls of member 12 and the friction plates 15 thereon.

Projecting from one of the plates 20 is a 15 pair of studs 23 that are adapted to pass through the apertures in certain styles of safety razor blades when the latter are positioned between the plates of the holder and formed in the lower edge of the other one of the plates 20 are 20 notches 24 for the accommodation of the ends of the studs 23 that project through the engaged razor blade.

Slots 24 are concentric with the axis formed by rivet 17.

25 The form of holder illustrated in Fig. 3 is especially designed for receiving and holding "Gillette" types of safety razor blades while the construction illustrated in Fig. 7 has the studs and slots spaced a greater distance apart so 30 as to conveniently receive and retain other types of safety razor blades such as the "Valet."

In Fig. 8, the plates 20 are illustrated as provided with longitudinally disposed slots 25 for the accommodation of reenforcing members 35 that are formed on certain makes of safety razor blades such as "Gem", "Star", "Ever-ready" and the like.

In the use of my improved holder, the plates 20 are swung into the positions as illustrated in 40 Fig. 3, so as to expose practically the entire inner face of the plate that is provided with the studs 23 and the blade to be sharpened is positioned on the plate that is provided with the studs with the latter projecting through the 45 apertures in the blade.

The ear 21 on the plate that is provided with the slots 24 is now swung around into position upon the plate on which the razor blade rests by pressure of the thumb or finger on the ear 50 21 of the slotted plate and when so positioned the razor blade is firmly seated between the two plates 20.

Both plates are now swung inwardly toward the holder so that their rear or upper edges pass 55 between the friction plates 15 and due to the resiliency in the metal of which the holder is formed and the spacing of the plates 15 relative to the thickness of the combined plates 20 and interposed razor blade, the blade holding plates 60 20 will be firmly gripped between the parallel plates 15 and the stropping operations may now be readily accomplished.

During blade sharpening operations, the covered handle 10 is held in the hand and during 65 the stropping strokes of the holder, the lower exposed edges of the ears 21 are engaged in succession by the thumb and finger, thereby effectually preventing the blade holding plate from shifting or moving out of their position between the friction plates 15 during the stropping 70 operation.

To open the holder for the purpose of removing or reversing the position of the blade, the thumb and finger engage in the apertures 22 75 in the ears 21 and by exerting outward pull on

said ears, the plates 20 will be swung outward away from the inverted U-shaped member 12 and after such operation the slotted plate 20 is swung away from the plate that is provided with the studs, thereby exposing the blade and permitting the ready removal or reversal thereof.

When a blade is positioned between the plates 20 and the latter are swung into the slotted forward portion of the handle, the straight upper edges of the plates engage against the upper portion of the handle opposite from the parallel friction plates 15 and thus a firm bearing is provided for said plates 20 throughout their lengths and the engagement of the perforated ears 21 in the slotted neck portion 14, together with the pressure of the friction plates 15 and the pivoting of the plates 20, to the forward end of the handle, functions to very firmly grip and hold the blade receiving plates within the holder and effectually preventing the same from tending to swing outwardly from the holder as a result of the friction developed during stropping operations between the blade and strop.

A decided advantage in the manipulation of the holder and particularly the blade receiving plates when the latter are opened or closed, resides in the construction whereby said plates are pivotally connected to the forward end of the body of the holder and the formation of the perforated ears 21 on the rear ends of said plates for, such construction plus the length of the blade engaging plates, produces or develops ample leverage to enable the plates to be readily swung outwardly from their position between the friction plates 15 on the portions 35 12 of the holder. Further, this particular construction enables the plates to be opened and closed with comparative safety against accidental injury to the hand and fingers as a result of contact with the exposed edges of the razor 40 blade that is positioned between the clamping plates.

In some instances it may be found desirable and advantageous to slot the body of the holder throughout its entire length and to form the 45 blade gripping plates 20 of a length equal to or slightly greater than the length of the holder so that the rear ends of said plates are engaged at the rear end of the handle of the holder when said plates are swung out of the holder and such 50 construction provides greater leverage to facilitate the opening or swinging outward of said plates and likewise provides a strong and substantial construction when the blade engaging 55 plates are folded into the holder and consequently retaining the inserted blade in firm position.

Thus it will be seen that I have provided a safety razor blade holder that is relatively simple in construction, inexpensive of manufacture and 60 very effective in performing the functions for which it is intended.

It will be understood that minor changes in the size, form and construction of the various parts of my improved safety razor blade stropping holder may be made and substituted for those herein shown and described without departing from the spirit of my invention, the scope of which is set forth in the appended claims.

I claim as my invention:

1. A stropping holder for safety razor blades, comprising a handle having a slotted forward portion, a pair of separately formed independently movable blade engaging plates pivotally

connected to the forward end of said handle and adapted to swing into the slot therein, means associated with the pivotal means between said plates and handle for holding one side of said handle against movement toward the other side, the width of which plates is such that their upper edges bear against the wall of the handle when said plates are swung into the slot in said handle the walls of said handle at the rear of said slotted forward portion being provided with a notch and flanges extending inwardly from the walls of the handle immediately above said notch for frictional engagement with the rear portions of the plates when the same are positioned within the slot in said handle.

2. A stropping holder for safety razor blades, comprising a handle having a slotted forward portion, a pair of separately formed independently movable blades engaging plates pivotally connected to the forward end of said handle

and adapted to swing into the slot therein, means associated with the pivotal connection between said plates and handles for holding one side of said handle against movement toward the other side, one of the blade engaging plates being provided with apertures, studs projecting from the other plate and adapted to extend into the apertures in the other plate when the two plates are folded together, the width of which plates is such that their upper edges bear against the wall and the handle when said plates are moved into the slot in said handle, the walls of said handle at the rear of said slotted forward portion being provided with a notch and flanges projecting inwardly from the walls of the handle immediately above said notch for frictional engagement with the rear portions of the plates when the same are positioned in the slot in said handle.

SOLOMON A. BEHRMAN. 20
